a corporation of Connecticut

Application February 27, 1952, Serial No. 273,679

7 Claims. (Cl. 183—37)

1

This invention relates generally to vacuum cleaners and more particularly to an improved construction for vacuum cleaners of the tank type having many advantages in manufacture and use.

It is the general aim of the invention to provide a sturdy, lightweight, tank-type vacuum cleaner of superior operating characteristics which may be simply and economically fabricated and assembled, which is compact in size and which functions in an improved and efficient manner and includes improved air flow characteristics enhancing the utility of the cleaner.

A more specific aim of the invention is to provide a vacuum cleaner of the tank type in which the filter section and motor compartment are vertically arranged in side-by-side relationship to form a compact machine having improved performance characteristics and in which novel and improved air flow control means are incorporated to enhance the utility of the cleaner. Included in this aim is the object of providing a tank type cleaner from which the dust bag may be vertically arranged and yet which is compact and stable in operation, simple in design, and efficient in operation.

A further object of the invention is to provide a vacuum cleaner of the type referred to in which the flow of air is conducted in a manner which will materially diminish the noise of operation of the cleaner and which includes manually adjustable means operable to vary the air flow path to suit the cleaner to the particular use or desired operation.

Another object of the invention is to provide a vacuum cleaner of large cleaning capacity, although small in size, which may employ an electric driving motor of relatively large rating under efficient operating conditions, particularly from the standpoint of temperature.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a longitudinal vertical cross-sectional view of a vacuum cleaner embodying the present invention.

Fig. 2 is a plan view of the cleaner with the top portion thereof removed to show the interior of the cleaner; and

2

Fig. 3 is a view similar to Fig. 1 and illustrating a modified construction of the cleaner.

As shown in the drawings, the operating elements of the cleaner are disposed within a generally rectangular box-like sheet metal housing 10 which for convenience in manufacture may comprise an upper shell or section 11, a lower shell or section 12, and a base 22. The upper and lower housing sections are provided with cooperating peripheral flanges 13 and 14, respectively, which are connected together as by screws 15. A channeled strip 16 of resilient material such as rubber or plastic surrounds the interconnected flanges to provide a bumper for the cleaner and cover the joint between interconnected sections of the housing.

The bottom wall 17 of the lower section 12 is provided with a pair of side-by-side openings 18 and 19 over which a dust separating unit indicated generally by the reference numeral 20 and a motor-fan unit 21 are located, respectively, in vertical side-by-side relation. The bottom wall 17 of section 12 forms a platform or false bottom for the housing, the section 12 being supported by the base 22 which has a generally vertical peripheral wall 23 telescopically receiving the lower peripheral portion of the section 12 as indicated at 24. The wall 23 is welded or otherwise secured in an air tight manner to the bottom portion of the section or shell 12 and the bottom wall 25 of the base being in spaced relation to the bottom wall 17 defines a compartment 26 therebetween which provides a wide air passageway of low pressure drop or air flow resistance interconnecting the openings 18 and 19 in the wall 17 of the housing. Reinforcing brackets 27 are disposed centrally of the housing to maintain the spaced relation between the bottom 17 of section 12 and the bottom wall 25 of the base. The base is provided with a plurality of downwardly struck sections 28 which act as runners or glides to support the cleaner on the floor or other surface.

The top of the housing is provided with a handle 29 above the motor-fan unit 21 and is provided with a hinged cover 30 over the dust separating unit 20 to give ready access to said unit. The cover 30 closes a circular opening 31 in the top of the housing, and a manually operable latch 32 is provided to release the cover so that the same can be swung aside.

The dust separating unit 20 is disposed within the circular opening 31 and comprises a paper filter bag 33 supported from a ring 34 within a cloth filter bag 35 supported from a ring 36.

The ring 36 has an outwardly directed flange 37 on which the ring 34 rests and the rings are supported by the top edge of a generally cylindrical container 38. The container 38 is supported on rubber rings 39 and secured as by screws 40 to the bottom wall of the housing so as to overlie the opening 18 therein. The bottom wall 41 of the container is perforate to accommodate the passage of air and a filter pad 42 of fibrous material or the like is disposed within the container 10 in spaced relation to the bottom wall thereof.

It will be understood from the foregoing description that if the motor-fan unit 21 is operated to withdraw air from the compartment 26, air will be drawn through the dust separating unit 20 through the filter pad 42 and perforated bottom wall of the container into the compartment 26. The cover is provided with an angularly disposed air inlet opening and fitting 45 which accommodates the usual hose or tube (not shown) which carries the dust collecting vacuum nozzle or other accessory. As the air is drawn through the fitting 45 into the filter unit 20, the paper and cloth dust separating bags 33 and 35 and the filter pad 42 remove the dust from the 20 air stream before the air is drawn into the motor-fan unit.

The motor-fan unit includes a conventional electric motor 50 electrically connected to the terminals 51 and arranged to be operated by a switch 52. The motor 50 has a vertically arranged drive shaft 53 to which the fan blades 54 are secured adjacent and above the opening 19. The motor and fan unit are supported within a casing which includes the upper and lower members 55 and 56, respectively, the member 56 having an opening 57 concentrically arranged with the fan and disposed concentrically to the opening 19 in the bottom wall of the housing. A vibration damping mounting for the motor-fan unit is included in the construction and comprises the rubber ring 60 which is secured as by rivets 61 to the lower section of the motor-fan casing and as by screws 62 to the bottom wall of the housing. An inverted cup-shaped housing 63 surrounds the motor-fan unit casing in spaced relation thereto and is secured by the screws 62 to the rubber ring 60 at the bottom wall 17 of section 12. A cloth hood or cover 64 is disposed over the motor-fan unit within the housing 63 to collect any dust present in the air drawn through the motor-fan unit and to diminish the operating sounds of said unit.

In the embodiment shown in Figs. 1 and 2 of the drawings, the upper portion of the container 63 is provided with a plurality (five shown) of openings 65 through which the air drawn by the motor-fan unit may be released. The air released through the openings 65 is received in the space within the housing 10 exteriorally of the container 63. Both longitudinal sides of the housing 10 are provided with a large number of elongated slots 66 which may be covered interiorly by porous sound absorbing and dust filtering pads 67. Accordingly, the air drawn by the motor-fan unit from the dust separating unit and compartment 20 through passageway 26 is expelled through the motor 50 and container 63 and from thence is discharged into the outer housing from which it escapes through the elongated slots 66. The expansion of air provided within the housing 10 and the relatively large exit openings provided by the slots reduces the velocity of the discharge at the individual slots,

thereby reducing the noise level accompanying said discharge.

In the event that it is desired to use the vacuum cleaner as a blower, means are provided for connecting a blower attachment and for closing off the openings 65 in the casing 63 which normally release the air to the interior of the housing 10. Said means includes a cover 70 rotatably mounted on the top of the container 63. The cover has a plurality of openings 71 which may be rotated into registry with the container openings 65 during normal operation of the cleaner and the cover is provided with a manually operable handle 72 extending through an opening 73 at the side of the housing 10 so that the cover can be rotated to a position wherein the container openings 65 are closed. Depending downwardly from the handle 72 is a plate 74 which is constructed and arranged to selectively close or open a conventional blower hose fitting 75 secured in the side of the container 63 in registry with an opening 76 in the side of the housing 10. The arrangement is such that when the cover 70 is in position for uncovering the container openings 65 the plate 74 is in obstructing position relative to the fitting 75 and when the cover 70 is turned to close the openings 65, the plate is moved to non-obstructing position permitting the coupling of a blower hose to the fitting. In the last mentioned position of the cover and plate, the air drawn by the motor-fan unit will, of course be released through the fitting 75.

A generally circular baffle 77 is preferably secured to the top of the cover member 70 to direct or deflect air released through the openings 65 outwardly and downwardly within the housing 10 to avoid turbulence and prevent the air which normally becomes heated during its passage through motor 50 from impinging directly against the top of the housing 10 which might otherwise cause the top of the housing 10 and the attached handle 29 to become unduly heated.

In Fig. 3 there is illustrated a modified and simplified construction of the vacuum cleaner which incorporates the compact side-by-side arrangement of the dust separating and motor-fan units described above and which also includes the unrestricted large air passageway therebetween. The modified form is more simply constructed in the interests of economy in the manufacturing process without departing from the aforementioned features of construction of the first described embodiment which enhance the performance characteristics of the cleaner. In the modified form the housing 80 is substantially identical to the housing 10 described in connection with the first form of the invention, and the motor-fan unit and the dust separating units enclosed within the housing are identical with the units utilized in the first described embodiment. The air passageway or compartment interconnecting the units is also identical to the passageway utilized in the first described construction, but the means utilized to control the flow path of air passing through the motor-fan unit is modified.

In the modified form, the motor-fan unit is enclosed in spaced relation by an inverted cup-shaped housing 81 mounted similarly to the first described housing 63 but formed without air release openings except for the air outlet opening 82. The air outlet opening 82 is provided with a hose fitting 83 in registry with an outlet 84 in the end of the casing 80.

As will be apparent from the foregoing description and from Fig. 3 of the drawings, the air drawn by the motor-fan unit and expelled through the motor to the interior of housing 81 all is released through outlet 82 and fitting 83. Accordingly, in this modification, it is not necessary to provide the housing 80 with air release slots as in the first described embodiment.

It has been found that as a result of the construction described above and including both embodiments, there is provided a vacuum cleaner of great utility having improved operating characteristics and which is particularly noted for its quiet and low temperature operation and superior cleaning action. The noise of operation is substantially reduced, the removal of dirt from the air is efficient, and the vertical side-by-side arrangement of the motor-fan and dust separating units with a wide passageway therebetween permits efficient functioning of the various elements. Furthermore, the cleaner is simple to handle and such steps as the removal and insertion of the dust bag or connection and disconnection of the attachments are easy and simple to carry out.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a vacuum cleaner of the tank type, the combination comprising an outer housing, a transverse wall spaced from the bottom of the housing and having a pair of side-by-side openings, said wall and the bottom of the housing forming a wide substantially unrestricted air passageway between the openings, a first vertically arranged compartment over one of said openings within and spaced laterally from the outer housing, a dust separating bag positioned in said first compartment, the outer housing having an opening registering with the first compartment for permitting vertical removal and insertion of the bag, a closure member having hose attaching means for said compartment, a second vertically arranged compartment over the second of said openings within and spaced laterally from the outer housing, a fan and driving motor disposed in the second compartment with the fan in communication with the opening and with the motor arranged to receive the air from the fan, and means for releasing air from the second compartment.

2. In a vacuum cleaner of the tank type, the combination comprising a generally rectangular outer housing, a pair of upright side-by-side cylindrical compartments within and laterally spaced from said housing, a platform spaced from the bottom of the housing and forming an enclosed wide air passageway therewith between the bottoms of the compartments, a dust separating bag positioned in one compartment, opening means in the outer housing to permit vertical insertion and removal of the bag, a fan assembly and a motor for driving same contained in the second of the compartments, means for releasing air from the second compartment with the axis thereof vertically arranged, means in the upper end of the second compartment forming a passageway for releasing air from the second compartment to the space interior of the housing but exterior to the compartments, and means forming a plurality of side-by-side air outlet openings in the side wall of the outer housing adjacent the bottom thereof for dispersing the air throughout a relatively large area.

second compartment with the axis thereof vertically arranged, means in the upper end of the second compartment forming a passageway for releasing air from the second compartment to the space interior of the housing but exterior to the compartments, and means forming a plurality of side-by-side air outlet openings in the side wall of the outer housing adjacent the bottom thereof for dispersing the air throughout a relatively large area.

3. In a vacuum cleaner of the tank type, the combination comprising an outer housing, a pair of vertical side-by-side compartments within and laterally spaced from said housing, a platform spaced from the bottom of the housing and forming an enclosed wide air passageway therewith between the bottoms of the compartments, a dust separating bag positioned in one compartment and depending from the upper end thereof, opening means in the outer housing to permit vertical insertion and removal of the bag, a fan assembly and a motor for driving same contained in the second compartment with the axis thereof vertically arranged, means in the upper end of the second compartment for releasing air from the second compartment to the space interior of the housing but exterior to the compartments, a baffle on the second compartment for directing air from the compartment away from the top of the housing, and means forming a plurality of openings in the side wall of the outer housing for dispersing air from said space over a relatively large area.

4. In a vacuum cleaner of the tank type, the combination comprising an outer housing, a pair of upright side-by-side compartments within and laterally spaced from said housing, a platform spaced from the bottom of the housing and forming an enclosed wide air passageway therewith between the bottoms of the compartments, a dust separating bag positioned in one of the compartments, opening means in the outer housing to permit vertical insertion and removal of the bag, a fan assembly and a motor for driving same contained in the second compartment with the axis thereof vertically arranged, said fan assembly being disposed adjacent said air passageway and said motor being disposed above the fan assembly but spaced from the interior surface of the second compartment, means in the upper end of the second compartment for releasing air from the second compartment to the space interior of the housing but exterior of the compartments, means forming a plurality of air dispersing openings in the side wall of the outer housing for dispersing air from said space over a relatively large area, and a porous pad covering said dispersing openings.

5. In a vacuum cleaner of the tank type, the combination comprising a pair of side-by-side compartments, an outer housing surrounding said compartments and providing an enclosed space therebetween, means forming a plurality of air dispersing outlets in the housing, means forming an enclosed air passage between the compartments, a dust separating bag positioned in one of the compartments, a generally vertically arranged fan assembly and a motor for driving same contained in the second of the compartments, means providing a horizontal opening in the housing and an opening in the second compartment registering therewith for receiving a hose coupling, a baffle movable toward and away from a position between said openings, means forming an air passageway between the second

compartment and the space within the housing but exterior of the compartments, a closure member for said air passageway movable toward and away from closing position, and an operating lever connected to said baffle and said closure member extending through a slot in said housing to the exterior thereof for selectively setting the baffle and closure member alternately in obstructing position.

6. In a vacuum cleaner of the tank type, the combination comprising a pair of upright side-by-side cylindrical compartments, an outer housing surrounding said compartments and providing an enclosed space therebetween, said housing having a plurality of air dispersing outlets in the side thereof, a platform spaced from the bottom of the housing and forming an enclosed air passageway between the bottoms of the compartments, a dust separating bag disposed in one of the compartments and vertically removable and insertable therein, a generally vertically arranged fan assembly and a motor for driving same contained in the second compartment, a cap on said second compartment having an air outlet opening therein for releasing air to the space interior of the housing but exterior of the compartment, a plate turnably mounted on the cap for movement toward and away from a position obstructing said air outlet opening, a handle attached to the plate and extending outwardly through a slot in the housing to permit manual setting of the plate, means forming a side opening in the housing and a side opening in the second compartment registering therewith for receiving a hose coupling, and a baffle depending from said handle for movement to a position between the last named openings when the plate is moved to non-obstructing position and away from said position when the plate is moved to obstructing position.

7. In a vacuum cleaner of the tank type, the

combination comprising a pair of upright side-by-side cylindrical compartments, an outer housing surrounding said compartments and providing an enclosed space therebetween, means forming a plurality of air dispersing outlets in the side of the housing, a porous pad covering said outlets, a platform within the housing supporting said cylindrical compartments and having means forming an enclosed air passageway therebetween, a dust separating bag disposed in one of the compartments, opening means in the outer housing to permit vertical insertion and removal of the bag, a fan assembly and a motor for driving same contained in the second compartment, a cap on said second compartment having an opening for releasing air from the second compartment to the space interior of the housing but exterior to the compartment, a closure member for said opening movable to and away from obstructing position, means forming a side opening in the housing and second compartment for receiving a hose coupling, a closure member for said side opening movable to and away from obstructing position, and a pivotally mounted handle extending outwardly through a slot in the housing and connected to said closure members for moving the members alternately to obstructing positions.
